SNAP ACTION SWITCH

Harold Tyzack, Schiller Park, Ill., assignor to Carter Parts Company, Chicago, Ill., a corporation of Illinois

Application December 10, 1954, Serial No. 474,343

4 Claims. (Cl. 200—67)

The present invention relates to a snap action switch, 15 and more particularly to an improved element for effecting movement of a movable contact by a snap action into and from engagement with a fixed contact.

It is an object of the present invention to provide a snap switch which is constructed and arranged so that the contacts are opened or closed with a snap action irrespective of the rate of movement of the force which is applied to the actuating mechanism of the switch.

It is another object of the present invention to provide a snap switch of the foregoing character in which the movable parts of the snap switch comprise three parts, two of which are spring elements, such parts being constructed and arranged so that the opposing forces of the spring elements cancel each other in such a manner that a state of static equilibrium is attained, thereby enabling the three component parts to be assembled in a sub-assembly and handled in production as such.

It is another object of the present invention to provide a snap switch of the foregoing character in which a novel arrangement of parts is provided so that a minimum of resistance to pivotal movement occurs thereby assuring consistent operation and long life of the switch.

It is still another object of the present invention to provide a snap switch of the foregoing character in which uniform operating characteristics can be obtained from standard parts without requiring adjustment of the aforesaid sub-assembly or the complete assembly, thereby aiding in reducing production costs to a minimum.

It is still another object of the present invention to provide a snap switch of the foregoing character in which the spring elements in the sub-assembly can be used with equal facility in either a double throw snap switch or a normally closed or normally open type of snap switch.

Other objects of this invention will appear in the following description and appended claims, reference being had to the accompanying drawings forming a part of this specification wherein like reference characters designate corresponding parts in the several views.

In the drawings:

Fig. 1 is a plan view of a normally open or closed snap switch embodying the present invention;

Fig. 2 is a section taken on the line 2—2 of Fig. 1;

Fig. 3 is a section taken on the line 3—3 of Fig. 2;

Fig. 4 is an end elevation of the embodiment shown in Figs. 1 to 3;

Fig. 5 is a section similar to Fig. 2 of a double throw snap action switch embodying the present invention;

Fig. 6 is a section taken on the line 6—6 of Fig. 5; and

Fig. 7 is an end elevation of the embodiment shown in Figs. 5 and 6.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also,

2

it is to be understood that the phraseology or terminology employed herein is for the purpose of description and not of limitation.

Referring now to the drawings a more detailed description of the present invention will be given. The embodiment shown in Figures 1 to 4 includes a housing 10 of insulating material having a front section 12 and a rear section 14 which are secured together by a pair of rivets 16. Pins 18 are an integral part of the section 14 and fit into mating holes in section 12 to aid in assembling the casing sections. Holes 20 may also be provided for use in mounting the switch unit.

The housing 10 has a cavity 22 within which is carried a sub-assembly of three parts, the contact carrier 24, the actuator 26 and the U-shaped rocker spring 28. Riveted to the stationary end of the contact carrier 24 is a terminal 30. These parts can be joined together as a sub-assembly, if desired, and can be inserted directly into the housing 10 as a single unit.

The contact carrier 24 is mounted in the housing 10 in cantilever fashion so that the end to which terminal 30 is attached will be rigidly held, and the opposite end will be free to move between the stationary contacts 32 and 34. The latter are directly connected with the terminals 36 and 38. The movable end of contact carrier 24 has the contacts 40 and 42 securely mounted thereon, and they are adapted to engage the stationary contacts 32 and 34.

The contact carrier 24 is formed by a stamping operation from any suitable conducting metal and has a U-shaped cut-out 44 by which a spring arm 46 is formed within the contact carrier arm 48. The free end of spring arm 46 has a V-shaped notch cut therein and the notch comes to a knife edge as can be seen in Figure 2. The V-shaped notch straddles the actuator 26 in the circular groove 50 which circumscribes the actuator, the knife edge of spring arm 46 being the only portion of the latter to be in engagement with the actuator 26.

The U-shaped rocker spring 28 has a V-shaped notch cut in one of its ends, and this notch also comes to a knife edge. This notch straddles the actuator 26 in the circular groove 50 but in a position diametrically opposite the spring arm 46, and, as in the case of spring arm 46, only the knife edge engages the actuator 26. The opposite end of the U-shaped rocker spring 28 has a slot 52 which receives a tongue 54 extending from the contact carrier arm 48. The edge 56 of contact carrier arm 48 comes to a knife edge so that when the rocker spring 28 tilts or pivots, in a manner to be described, the bearing surface between the rocker spring 28 and the contact carrier arm 48 is limited primarily to the knife edge 56. Thus, it can be seen that substantially the only points of engagement between the three movable parts, the contact carrier 24, the actuator 26 and the rocker spring 28 are knife edges and those in the groove 50 are essentially point contacts so that the tilting or pivoting action that occurs between these parts is practically frictionless.

In the normal operation of this embodiment of the invention, the coil spring 58 will urge the actuator 26 to its uppermost position in the housing 10 with the push button end portion of the former projecting through the opening 60. The movable contact 42 will be in engagement with contact 34 so that the terminals 30 and 38 may be connected in either a normally open or normally closed circuit, as desired.

The contact 42 can be moved away from stationary contact 34 and contact 40 moved into contact with stationary contact 32 by a snap action merely by pressing down on the button end of actuator 26. With the switch in the position shown in Figure 2 the rocker spring 28 is in a state of compression so that the ends are exerting

an equal but opposite thrust against the actuator 26 and the contactor arm 48. Since the ends of the rocker spring 28 are in a plane that is inclined to the plane of the contactor arm 48, the spring 28 will exert a component of pressure tending to hold the contact 42 against stationary contact 34. However, when the plane containing ends of the rocker spring 28 passes into and thereafter tilts beyond the plane of contactor arm 48, there will be a component of force acting to move the free end of contactor arm 48 upward with a snap action into engagement with the contact 32. Immediately upon release of the button end of actuator 26 the coil spring 58 will move the actuator 26 to its elevated position shown in Figure 2 and as the ends of the rocker spring 28 pass through the plane of the contactor arm 48 the forces exerted by the rocker spring 28 will be such as to cause the sub-assembly to return to the position shown in Figure 2. In order to aid in maintaining uniform operation of the switch and to assure that the snap action will occur at substantially the same position of movement of the actuator 26, the edges of the contactor arm 48 are folded over as at 60, thereby preventing bowing of the contactor arm 48 and assuring that it will remain in substantially one plane during operation of the switch.

From the foregoing it can be seen that the movements of the component parts are substantially frictionless and the parts are supported so that there can be no misalignment or shifting which may cause irregular operation. Since the parts will encounter substantially no wear nor is there any likelihood of damage, a very long life is assured.

The present invention is not limited in use to a precise switch of the type described above. Other applications of the invention can be made, and one such application is illustrated in Figures 5 to 7. This modification is the same as the one previously described, but it is a double throw switch which has an actuator 26a which projects through the openings 60a in both the top and bottom of the housing 10a. Thus, the contacts 40 and 42 will remain in engagement with whichever of stationary contacts 32a or 34a as may be selected, merely by pressing the actuator 26a to its upper position shown, or to a corresponding lower position which will cause contact 40a to be in engagement with stationary contact 32a. In other respects this modification is the same as the one illustrated in Figures 1 to 4 and reference is made to the description of that modification for any of the other parts of the present modification.

Having thus described my invention, I claim:

1. In a snap action switch, a contactor element comprising a spring blade having a U-shaped cut-out so as to form a flat spring arm within a contactor arm, the free end of said spring arm having a V-shaped knife edge, a rocker spring pivotally connected to said contactor arm and having an end with a V-shaped knife edge disposed opposite to the corresponding edge of the spring arm, and an actuator extending axially through the cut-out of the spring blade, said actuator having a circumferential

groove for receiving said knife edges so that each of the latter straddles said actuator making point contacts therewith and the spring arm and rocker spring are movable on axial movement of said actuator, said actuator also having a spring for urging the spring arm and rocker spring in one direction and a push button for manually moving these elements in the opposite direction.

2. In a snap action switch, a contactor element comprising a spring blade having a U-shaped cut-out so as to form a flat spring arm within a contactor arm, the free end of said spring arm having a V-shaped knife edge, a rocker spring pivotally connected to said contactor arm and having an end with a V-shaped knife edge disposed opposite to the corresponding edge of the spring arm, and an actuator extending axially through the cut-out of the spring blade, said actuator having a circumferential groove for receiving said knife edges so that each of the latter straddles said actuator making point contacts therewith and the spring arm and rocker spring are movable on axial movement of said actuator, said actuator also having push buttons on its opposite ends for selectively moving the spring arm in opposite directions.

3. In a snap action switch, the combination comprising a fixed contact, a contactor element including a spring blade with a U-shaped cut-out so as to form a spring arm within a contactor arm, the free end of said spring arm having a V-shaped knife edge, a rocker spring pivotally connected to said contactor arm and having an end with a V-shaped knife edge disposed opposite to the corresponding edge of the spring arm, and an actuator rod extending axially through the cut-out of the spring blade, said actuator rod having a circumferential groove for receiving said knife edges so that each of the latter straddles said actuator rod making point contacts therewith, said spring blade carrying a contact movable into contact with said fixed contact so that movement of said actuator rod will effect movement of the movable contact by a snap action into and from engagement with the fixed contact.

4. In a snap action switch, the combination defined in claim 3 wherein the lateral edges of said contactor arm opposite the cut out of the blade are bent over to prevent bowing of this portion of the contactor arm.
